**N-(α -CYCLOALKENYLBENZYL) PIPERAZINES
AND METHOD OF MAKING**

Richard Baltzly, Tuckahoe, and Peter B. Russell, Crestwood, N. Y., assignors to Burroughs Wellcome & Co. (U. S. A.) Inc., Tuckahoe, N. Y., a corporation of New York

No Drawing. Application July 27, 1954,
Serial No. 446,169

9 Claims. (Cl. 260—268)

This invention relates to a family of compounds represented by Formula I in which R' is a lower alkyl group and R is selected from the class consisting of the Δ^2 -cyclohexenyl and the Δ^2 -cycloheptenyl radicals. The bases and acid addition salts of this formula have marked anti-histaminic properties while the mono quaternary salts of Formula II are powerful spasmolytics especially in those cases wherein the phenyl radical has no para substitution. This is a continuation-in-part of application Serial No. 409,764 filed February 11, 1954.

I

II

This invention also embraces a method of preparing these compounds. For this purpose we employ the sulfonate, especially the p-toluene sulfonate esters of Formula III (wherein n is 4 or 5) and which are described in a co-pending application.

III

When these tosylates (III) are made to react with bases, the elements of toluenesulfonic acid are eliminated, giving rise to unsaturated Compounds Ia. When the base employed for this elimination is fairly bulky (as sodium or potassium t-butoxide, collidine or 2,6-lutidine) the elimination is unilateral and unaccompanied by detectable side reactions so that Ia is isolated with ease in good yield and in high purity.

Ia

While for preparative purposes the p-toluene sulfonates are generally employed, this is due to cheapness and availability of p-toluene sulfonyl chloride. Other hydrocarbyl sulfonates such as benzene sulfonates, p-bromobenzenesulfonates, methane sulfonates etc. behave similarly and their use is considered to be included in the invention.

For conversion of bases (I or Ia) to the quaternary ammonium salts, the bases are dissolved in a suitable solvent (e. g., acetone) with somewhat more than an equivalent of alkyl halide and allowed to stand, or in some cases refluxed. The quaternary salts (II) crystallize

2

substantially pure but may be recrystallized from alcohol or alcohol-ether mixtures. In the Formula II, X⁻ may be any convenient anion, preferably derived from the alkyl halide employed. In the earlier stage of operations 5 X⁻ is most frequently iodide but for therapeutic purposes chloride, bromide, ethane sulfonate, toluene sulfonate would probably be preferable. However, since these compounds are extremely potent and would seldom be given in doses exceeding 1 to 2 mg., the identity of the anion is actually of no significance.

Aside from their intrinsic value, the unsaturated bases of this invention can be reduced catalytically to the corresponding dihydro derivatives which are the subject of a co-pending application. This reduction may be accomplished by any of the common catalysts, preferably however, those not especially addicted to de-benzylation. Adams' platinum catalyst, platinized charcoal or Raney nickel are all satisfactory.

EXAMPLE 1

N-methyl-N' [α -cyclohex-2-enylbenzyl]piperazine: By potassium tert. butoxide

To a solution of potassium tert. butoxide (from 12 gms. potassium) in tert. butanol (900 cc.) was added the p-toluenesulfonate ester of trans-N-methyl-N' [α -(2-hydroxycyclohexyl)benzyl] piperazine (30 g.). The solution was refluxed for 20 hours and then the tert. butanol removed in vacuo. The residue was dissolved in water and the solution extracted with ether. The basic fraction was removed from the ether with 2 N hydrochloric acid. The acid solution was basified and the separated base taken up in ether. The ether was removed after washing and drying the solution. The residue was distilled to give 15 g. clear oil, B. P. 80° (bath temp.)/.2 mm. 35 The material solidified; recrystallized from pentane it formed needles M. P. 84°.

On catalytic reduction this compound gave N-methyl-N' [α -cyclohexylbenzyl] piperazine identical with a previously described sample.

On treatment with methyl iodide in acetone the above base gave a quaternary salt. After recrystallization from ethanol/ethyl acetate this salt formed prisms M. P. 205—206°.

With ethyl iodide the corresponding ethiodide M. P. 45 180—181° after recrystallization from ethanol/ethyl acetate resulted.

With isopropyl iodide the corresponding quaternary salt melted at 217—220°.

With ethyl p-toluenesulfonate a quaternary was formed 50 which melted after recrystallization from ether/ethanol at 107—108° with foaming.

EXAMPLE 2

N-methyl-N' [α -cyclohex-2-enylbenzyl] piperazine: By heating with 2,6 lutidine

The tosylate (5 g.) was dissolved in 2,6-lutidine (25 ml.) and the mixture heated on a steam bath for 72 hours. The solution was then diluted with water and the aqueous solution extracted three times with ether; the ether was removed and the residue dissolved in pentane; after washing the pentane solution several times with water, it was dried and then evaporated. The residue 2.3 g. crystallized M. P. 83° underpressed on admixture with the sample of N-methyl-N' [α - Δ^2 -cyclohexenylbenzyl] piperazine described above.

EXAMPLE 3

N'-methyl-N' [α -cyclohex-2-enyl-o-chlorobenzyl] piperazine

Trans - N' - methyl - N - [α - (hydroxycyclohexyl) - o - chlorobenzyl] piperazine p-toluene sulfonate (1.3 g.) was

3

added to tert. butoxide (from 0.3 g. potassium) in butanol (20 ml.). The mixture was refluxed for 16 hours in the usual manner and then worked up as previously described. The resin boiled at 95-100° (bath temp.)/0.1 mm. (0.8 g.).

EXAMPLE 4

N'-ethyl-N-[α -cyclohex-2-enylbenzyl] piperazine

This compound was prepared by treating the corresponding alcohol trans p-toluenesulfonate (3 g.) with potassium tert. butoxide (from 0.2 g. K) in the usual manner. The product (1.6 g.) boiled at 100° (bath temp.)/0.15 mm. Catalytic reduction of this material gave *N*-ethyl-*N'*-[α -cyclohexylbenzyl] piperazine identical with previously described samples.

In acetone solution the unsaturated base reacted with ethyl ethanesulfonate to give *N,N*-diethyl-*N'*-[α - Δ^2 -cyclohexenylbenzyl] piperazinium ethane sulfonate.

EXAMPLE 5

N-methyl-N'-[α - Δ^2 -cycloheptenylbenzyl] piperazine

The tosylate of 2- α -[*N*'-methyl-*N*-piperazino] benzylcycloheptanol (3 g.) was dissolved in 2,6-lutidine (25 ml.) and the solution heated on the steam bath for 36 hours. The mixture was dissolved in pentane and washed 5 or 6 times with water. The pentane solution was dried and the solvent removed. The residue (2 g.) was distilled, the distillate (B. P. 95-100° [bath temp.] 0.1 mm.) was a pale yellow oil.

On hydrogenation with a platinum catalyst it gave *N*-methyl-*N'*-[α -cycloheptylbenzyl] piperazine the ethyl iodide of which was identical with an authentic sample.

The unsaturated base gave with ethyl iodide an ethiodide M. P. 177° (dec.) after recrystallization from acetone-ethyl acetate.

What is claimed is:

1. A compound selected from the class consisting of the free base, acid addition salts and mono-quaternary salts, derived from therapeutically acceptable acids, of compounds having the free base formula:

wherein Ar is a phenyl radical, alk is a lower alkyl radical and n is an integer from 3-4.

2. *N*-methyl-*N'*-[α -cyclohex-2-enylbenzyl] piperazine.
3. *N'*-ethyl-*N*-[α -cyclohex-2-enylbenzyl] piperazine.
4. *N*-methyl-*N'*-[α - Δ^2 -cycloheptenylbenzyl] piperazine.
5. The method of preparing a compound represented by the formula

10 15 which comprises reacting a compound of the formula

20 25 wherein Z is a hydrocarbon radical and n is an integer from 3-4, with a base and recovering the unsaturated product.

6. The method of claim 5 wherein the tosylate is reacted with an alkali t-butoxide.
7. The method of claim 5 wherein the tosylate is reacted with 2,6-lutidine.
8. A salt of a therapeutically acceptable anion with the *N*-methyl-*N'*-ethyl- $(\alpha$ - Δ^2 -cycloheptenylbenzyl) piperazinium ion.
9. A salt of a therapeutically acceptable anion with the *N,N*-diethyl- $(\alpha$ -cyclohex-2-enylbenzyl) piperazinium ion.
